DESIGN FOR A REFRESHMENT BOOTH

Mervin O. Symons and Richard Davis,
Los Angeles, Calif.

Application May 20, 1946, Serial No. 129,873

Term of patent 3½ years

(Cl. D13—1)

To all whom it may concern:

Be it known that we, Mervin O. Symons and Richard Davis, citizens of the United States, residing at Los Angeles, county of Los Angeles, and State of California, have jointly invented a new, original, and ornamental Design for a Refreshment Booth, of which the following is a specification, reference being had to the accompanying drawing, forming part thereof.

The figure is a three-quarter front perspective view of a refreshment booth, embodying our new design.

We claim:

The ornamental design for a refreshment booth, substantially as shown.

MERVIN O. SYMONS.
RICHARD DAVIS.
